UNITED STATES PATENT OFFICE.

FRANK DUTCHER, OF MCKEESPORT, PENNSYLVANIA.

RAILWAY SIGNAL TORPEDO.

Application filed April 14, 1924. Serial No. 706,361.

To all whom it may concern:

Be it known that I, FRANK DUTCHER, a citizen of the United States, residing at Versailles Boro., McKeesport, in the county 5 of Allegheny and State of Pennsylvania, have invented certain new and useful Improvements in Railway Signal Torpedoes, of which the following is a specification, reference being had therein to the accompanying drawing.

This invention relates to improvements in railway signal torpedoes, and the improvements herein pertain to the construction of a clip to which a rail-engaging strap is attached.

The primary object of my present invention is to construct a clip in the form of a circular disk having its edges corrugated, the said disk adapted to be held or clamped by 20 an expanded flange of the torpedo case.

A further object of the invention is to construct the disk-formed clip with an annular corrugation whereby the clip is prevented from being distorted out of shape 25 under compression.

Further objects of the invention will appear from the following specification.

In the accompanying drawings—

Figure 1 is a perspective view of the under 30 side of a torpedo with my present invention applied thereto.

Fig. 2 is an enlarged transverse sectional view of the torpedo showing the improved clip applied to it.

Fig. 3 is an enlarged transverse sectional view of the torpedo, showing a modified form 35 of connecting the clip with the case.

Fig. 4 is an enlarged plan view of the clip shown in Figs. 1 and 2.

Figs. 5, 6 and 7 are enlarged plan views 40 each showing a modification in the clip.

In the drawings, I have shown the clip applied to a circular torpedo case, but I desire it to be understood that broadly the shape 45 of the case is immaterial. Furthermore, the formation of the case is immaterial to the broad idea. It will be understood from the following description that the shape of the clip will be the same as the shape of the case 50 whether it be round or other shape.

Referring now to the drawings, 1 designates the case, which as stated may be made in two telescoping parts as here shown, or in any other desired manner. In the form 55 of torpedo case as shown in Figs. 1 and 2, the case involves a surrounding strengthening

ring 2, which is made wider or deeper than the case, to provide the case with a depending flange. However, as will appear herein-after, the outer part of the case may be provided itself with a depending flange, so that in the appended claims the term of a case provided with a depending flange is to be considered broad enough to include either the ring or the case itself, unless it be otherwise 60 specifically stated in some of the claims.

The improved clip 3 is in the form of a disk, here shown annular in plan view, though it will be made of a shape to fit a torpedo case, if the case be made in other form. 70 The disk 3, as shown in Fig. 4, is provided with a plurality of projections 4.

This disk is also provided with openings 5, and cut away portions 6 in its periphery, and the rail-engaging strap is made in two 75 parts 7 when in the form of a spring strap, but if a lead strap 8 is used, it will then be made of a continuous piece, as shown in dotted lines Fig. 6. The form of the strap is not material to the present invention, 80 since the form of spring strap shown in Fig. 2 is made the subject-matter of a co-pending application, Serial No. 706,358, filed April 14, 1924, and no claims are made herein to it.

When the strengthening ring 2 is used, the clip 3, is preferably placed within the strengthening ring 2, and when the case is applied to the strengthening ring, which it fits very tightly, then the projections 4 90 of the clip are forced in the ring sufficiently to hold it there tightly.

In Fig. 3 the projections 4 are made pointed, as shown at 9 in the said figure, and are forced through the depending flange 10 of the outer part of the case, being clinched on the outer side of the flange. In this construction, the clip serves to hold the case from separating, and the surrounding ring may or may not be used.

In Fig. 5, the clip 3 has its periphery provided with only a few projections 11, and these projections may be pointed, as shown, to go through the case and be clinched, or the projections may be made 100 blunter, as in Fig. 4.

Figure 6 shows an eight sided clip, which forms points 12 that will engage the depending flange of the case, serving to clamp the clip on the torpedo.

In Fig. 7, the clip 3 is of an eight sided shape and may have its points 13 pointed

as shown, to be clinched through the depending flange.

I desire it to be understood that when the projections are sufficiently pointed to pass through the flange and be clinched on the outer side, they may go through one part of the case, as shown in Fig. 3, or may go through the depending flange formed by the strengthening ring 2.

10. All the clips in all the figures are provided with an annular outwardly extending corrugation 14, the function of which is to strengthen the clip, whereby it is prevented from buckling under pressure.

15. I have not attempted to show the different shapes of the torpedo case, nor the different shapes of the clip, as they are to be made to correspond with the case, but have only shown some of the forms that may be used.

20. Having thus described my invention, what I claim and desire to secure by Letters Patent is:

1. A railway signal torpedo comprising a case having a depending peripheral flange, 25 and a disk-shaped clip having a periphery within and forceably engaging the inner side of the flange, the clip held to the torpedo by the said flange.

2. A railway signal torpedo comprising a 30 case having a depending flange, of a disk shaped clip having peripheral projections adapted to be clamped by the said depending flange.

3. A railway signal torpedo comprising a 35 case having a depending flange, a disk-

shaped clip applied to the torpedo and provided with pointed projections adapted to engage and be held by the depending flange of the case.

4. A railway signal torpedo comprising a 40 case having a depending flange, of a disk-shaped clip having a plurality of sharpened projections adapted to penetrate the flange and be clinched, for the purpose described.

45. A railway signal torpedo comprising a case having a depending flange, a disk-shaped clip applied to the case, said clip having throughout its periphery a plurality of projections engaged by the flange, said clip having strap receiving openings.

50. A railway signal torpedo comprising a case having a depending flange, a disk-shaped clip held to the case by means of the flange, the said clip having an outwardly 55 extending annular strengthening corrugation.

55. A disk-shaped clip for torpedoes, the said disk having on its periphery a plurality of projections extending in the plane of disk and constructed to receive and hold 60 the rail-engaging strap.

65. A clip for torpedoes comprising a disk having throughout its periphery a plurality of projections and an annular outwardly extending corrugation, for the purpose described.

In testimony whereof I hereunto affix my signature.

FRANK DUTCHER.
